UNITED STATES PATENT OFFICE

125,963

DESIGN FOR A DRAPE

Leon Cohen, Philadelphia, Pa.

Application September 18, 1940, Serial No. 95,180

Term of patent 7 years

To all whom it may concern:

Be it known that I, Leon Cohen, a citizen of the United States and a resident of Philadelphia, in the county of Philadelphia and State of Pennsylvania, have invented a new, original, and ornamental Design for a Drape, of which the following is a specification, reference being had to the accompanying drawing, forming a part thereof.

In the drawing, the figure is a front elevational view of a drape showing my new design.

I claim:

The ornamental design for a drape, as shown.

LEON COHEN.
